 a corporation of New York

Application August 19, 1936, Serial No. 96,847

9 Claims. (Cl. 74—1)

This invention relates to regulators of the type including a condition-responsive unit and means actuated thereby for controlling the application of a medium to prevent any deviation from a predetermined condition.

The present invention has for its purpose the production of a regulator of the mentioned type having a high degree of accuracy, long life and relatively low manufacturing cost.

10 The various features of the invention will appear from the detailed description and claims when taken with the drawings in which Fig. 1 is a front elevation of the regulating mechanism, the frame and case thereof being omitted; Figs. 15 2 and 3 are plan views of an overrun or protective mechanism whereby abnormal operations applied by the condition-responsive mechanism will not be transmitted to the actuating mechanism of the instrument, Fig. 2 showing the overrun mechanism in one of its limiting positions and Fig. 3 showing the mechanism in its other limiting position; Fig. 4 is a fragmentary elevational view of the overrun mechanism of Figs. 2 and 3; Figs. 20 5 and 6 are different perspective views of the actuating mechanism interposed between the condition-responsive unit and the regulating member or members to be selectively positioned; Fig. 7 is a sectional view taken substantially on the line 7—7 of Fig. 1; Fig. 8 is a similar sectional view taken on the line 8—8 of Fig. 1; and Figs. 9 and 10 are respectively sectional views similar to Figs. 7 and 8 showing the mechanism in a different operating position.

Referring to the drawings, the numeral 5 designates a bulb connected by a capillary tube 6, to a Bourdon spring 7, these elements together constituting a tube system which is filled with a thermosensitive medium. A take-off 8 attached to the free end of the Bourdon spring is connected 35 by a link 9 to a pen arm bracket 10. This bracket is pivotally mounted on a pedestal or support 11 and carries a pen arm 12 which is provided at its free end with a stylus 13 positioned in operative relation to a chart 14. This chart is arranged 40 to be rotated by a suitable clock mechanism of which only the hub is illustrated.

The pen arm bracket 10 is connected by a link 45 16 to the bracket 18 of a control arm 19 mounted on the arbor 20 for rotation on a pedestal or support 21. The connection between the link 16 and the control arm bracket is a yielding or "overrun" connection, so that if the link 16 is moved to the right or to the left beyond predetermined limits, there will be no injury to the control arm bracket or its mounting. This overrun

connection which is best illustrated in Figs. 2, 3 and 4 includes an arm 22 to which one end of the link 16 is connected, as indicated at 23, the arm being fixed to a hub 24 which is rotatable on the arbor 20, previously mentioned as rotatively mounted in the pedestal or support 21. The hub 24 has a groove 26 extending around its periphery which groove receives a loop formed at one end of a rod 27 so that the rod can swing in the groove on the hub. A coil spring 28 encircles the hub 24 and has one of its ends hooked to the arm 22 and has its other end hooked to the rod 27 so that the rod and arm are normally in superimposed relation, being stopped in this position by pin 29 which projects from the arm 10 into engagement with one side of the end portion of the rod. The control arm bracket 18 is also provided with a hub 30 secured thereto, which hub is attached to the arbor 20. A second coil spring 31 encircles the hub 30 and has one of 20 its ends engaging the rod 27 while its other end engages a pin 32 projecting upwardly from a part of the bracket 18 so that the rod 27 is normally held against the stop pin 32. Thus the arm 22, the rod 27 and the control arm bracket 18 are 25 normally held in superimposed relation, but under abnormal forces in either direction these several parts assume respective positions shown in Figs. 2 and 3. By this arrangement the control arm bracket is accurately centered without any 30 play or lost motion.

The swinging control arm 19 is provided at its free end with a shoe 36 which moves in the arc of a circle but its outward movement with respect to the frame of the instrument, is limited by a strip 37 mounted in spaced relation to the frame.

It will be understood that in response to changes in temperature at the bulb 5, the free end of the Bourdon spring will either wind up or unwind with the result that it will transmit its motion through the links 9 and 16 to swing the control arm 19 and its shoe 36 in a corresponding manner. In order to sense periodically the position of the shoe 36, there is provided a mechanism to be described, to determine at which side of the control point the shoe happens to be located at any particular time. This mechanism includes a constantly operated driving motor 38 on the shaft 39 of which there is provided a four-point cam 40 (see Figs. 7 and 9). This cam, as it rotates, engages a suitable roller 41 carried on an extension of the follower arm 42 forming a bell-crank lever. The arm 42 is pivotally mounted on a shaft 45 which is supported in parallel relation to the back or frame of the device so that under 55

the control of the cam 40, the arm tends to rock about the shaft. A coil spring 46 normally maintains the arm 42 with its free end in its outward position, as illustrated in Fig. 7, except when it is depressed by cam 40.

There is also pivotally mounted on the shaft 45, a depressor arm 48 which is provided at its free end with a curved portion 49 bearing a contact plate 50 adjacent the arcuate path of travel 10 of the shoe 36. This plate in certain positions of the control arm encounters the shoe 36 for a purpose to be described. It will be noted that the arm 42 is provided with an extension 47 having mounted therein an adjustable screw to contact 15 an edge of the depressor bar 48. Thus when the arm 42 has its free end swung toward the frame under the action of the roller 41 and cam 40, the screw on this extension will engage the edge of the depressor bar to move the control plate 50 at its 20 free end, toward the frame, thereby spacing the plate 50 from the strip 37 so that the shoe 36 has an opportunity to swing therebetween. The free end 49 of the depressor bar 48 is normally held in its outward position by a coil spring 35, except 25 when it is depressed by the cam 40 through arm 42 and its lug 47.

At an intermediate point on the depressor bar 48 there is pivotally mounted a selector member 52, the rotary movement of this cam about its 30 pivot 53 being limited by a pin 54 projecting from the depressor bar into a notch 55 in the cam. By this arrangement the swinging movement of the cam is limited to movement between its two extreme positions illustrated in Figs. 7 and 9. The 35 selector member 52 is also provided with a pin 56 projecting therefrom. An upright 57 projecting from the frame terminates in a strip or hook 58 in a position to engage one side of the pin 56, while the other side of the pin is engaged by the 40 end portion of the follower arm 42. The selector member 52 is also provided with an extension 59 movable therewith, as will be hereinafter set forth, to project into the path of either of the pins 60 and 61 which function with switch-actuating 45 mechanism to be described, to move electrical switching means either to an open or to a closed condition.

The pin 60 is carried at the free end of one leg of a U-shaped lever 62 which is pivoted for 50 rocking movement on the shaft 63. The shaft 62 is supported, in parallel relation to the shaft 45, in the spaced uprights 64. The pin 61 is similarly carried at the free end of one of the legs of a second U-shaped lever 65 which is likewise pivotally supported on the shaft 63. The U-shaped lever 62 has secured to its upper end a positioning bracket 66 which preferably carries a counter-weight 67. The free end of this bracket is provided with a pin 68 which projects into a slot 70 55 in an arm 71 extending from a switch-adjusting yoke 72. This yoke, which is preferably U-shaped, is supported for rocking movement on the pins 73 and 73a in the spaced uprights 74 and is provided with pairs of spring fingers 75, each 60 pair being adapted to resiliently engage a mercury bottle-type switch 76. The U-shaped lever 62 has a pin 77 projecting from the other leg thereof on which the intermediate portion of a lever 78 is pivotally mounted. One end of this 65 lever is slotted to receive a pin 79 carried on the second leg of the U-shaped member 65, while the other end of the lever 78 is slotted to engage the pivot pin 78 on which one end of the yoke is supported. It will be noted in Figs. 8 and 10 that 70 the positioning bracket 66 is notched as indicated 75

at 83 and 84. These notches are adapted to be engaged by a spring 85 whereby the positioning bracket and the switch yoke actuated thereby are held in the respective positions to which they have been adjusted. The mounting of the U-shaped levers 62 and 65 and their interconnections thru the lever 78 are effective so that when the pin 61 on the lever 65 is depressed toward the frame of the instrument, the lower end of the other lever 62 and the pin 60 carried thereon, are moved outwardly with respect to the mentioned frame. Similarly when the pin 60 on lever 62 is depressed, the lower end of the lever 65 and the pin 61 carried thereon are moved outwardly from the frame of the instrument. These movements of levers 62 and 65 are effected as follows (see Fig. 6): When the pin 60 on the free end of the lever 62 is depressed, the mentioned lever swings about the shaft 63; thus the opposite end of the lever 62 carrying the pin 77 is elevated. Since the upper 20 end of the lever 78 swings about the fixed pivot pin 73, when the pin is elevated, it swings the lower end of the lever 78 outward about the pivot 73. This elevates the pivot pin 79 connected to the lower end of the lever 78 and to one of the 25 arms of the lever 65, so that the free end of the lever 65 and its pin 61 are elevated. Reversely, when pin 61 on lever 65 is depressed, the pivot pin 79 carried by this lever is depressed with the result that the lever 78 is swung to its depressed 30 position about the pivot pin 73. In this way the pivot pin 77 depresses the upper end of the lever 62 causing it to swing its opposite end outward to elevate the pin 60. Thus the levers 62, 65 and 78 constitute a reversible lever system, which is 35 effective to rock a controlling switch or other controlling member from one of its alternate positions to the other.

Briefly, the operation of the control mechanism is as follows: If the temperature about the 40 bulb 5 increases, the thermosensitive medium in the tube system expands causing the Bourdon spring 1 to unwind. The free end of this spring, operating thru the take-off 8 and the link 9, swings the pen arm 12 in a clockwise direction. 45 The link 16 which is connected to the pen arm bracket communicates this motion through the "overrun" mechanism of Figs. 2, 3 and 4, to swing the control arm 19 and its shoe 36 in a clockwise direction. It will be understood that during the 50 operation of the mechanism, the motor 38 is continuously operated to rotate the cam wheel 40 in the direction indicated by the arrow in Figs. 7 and 9. The roller 41 carried on the follower arm 42 in following the contour of the cam, periodically causes the free end of the arm 42 to swing toward the frame of the instrument, the reverse movement of the arm 42 being effected by the springs 35 and 46. While arm 42 is being depressed the extension 47 thereon engages the 60 depressor bar 48 to move the contactor 50 on the free end of this bar away from the stop 37 so that the shoe 36 can swing freely between the contactor and the stop 37. If, on the reverse motion of arm 42, the shoe 36 has moved into the path 65 of the contactor 50, the outward movement of the free end of the depressor bar is limited to the position shown in Fig. 7. Under these conditions the arm 42 on its continued forward motion will engage the pin 56 on the selector member 52, thereby swinging this member to its alternate position as shown in Fig. 7, wherein extension 59 is in the path of the pin 60. If, however, the shoe 36 is out of the path of the contactor 50 on the free end of the depressor bar, the latter will con- 70 75

tinue to move forward and the pin 56 on the selector member 52 will strike against the fixed hook 58. The continued motion of the depressor bar 48 will then cause the selector cam 52 to rotate about its pivot 53 until the left surface of its notch 55 strikes against pin 54, thereby stopping the forward motion of the depressor arm. The follower arm 42, depressor arm 48 and selector member 52 will then be in the position shown in Fig. 9 and the extension 59 will be in the path of pin 61 on lever 65.

Let it be assumed that the selector member 52 is positioned so that its extension 59 is in the path of the pin 60 as shown in Fig. 7. Thus when the depressor arm 48 is depressed, it will force the pin 60 and the lower end of the lever 62 toward the base of the instrument. This will be effective to elevate the pivot pin 77 on the other end of this lever. The lever 78 since it is pivotally connected to the lever 65 and since it engages the fixed pivot pin 73, swings the pivot pin 78 outward. This elevates the lower ends of lever 65 and the pin 61 carried thereon. When the lower ends of the lever 62 are depressed, this lever elevates the bracket 66 and the arm 68 carried thereby. A pin 69 on the free end of the arm engages the slot 70 in the arm 71 attached to the yoke 72. Thus the yoke 72 is swung to its depressed position wherein one or more mercury bottle-type of switches 76 are moved to one of their extreme positions.

Let it now be assumed that the selector member 52 is positioned so that its extension 59 is in the path of the pin 61. When the depressor arm 48 is again depressed, the extension 59 on its selector member will depress the pin 61 on the lower end of lever 65. As previously explained, this results in swinging the lower end of lever 62 outward. The arm 68 at the upper end of lever 62 is depressed so that the yoke 72 is elevated and switches 76 are rocked to their alternate position. Thus when the contactor 50 engages the shoe 36 on the control arm, the switches 76 are moved to one position, whereas when the movement of the contactor 50 is not obstructed by the shoe 36, the switches 76 are moved to their other position. When the shoe 36 is just barely touching the contact plate 50 without interfering with the motion of the latter, the control arm 19 is in its normal control position corresponding to the desired control point, and the pen arm 12 moving in unison with the control arm will indicate the control point on the chart. In order to change the control point, the relative positions of pen arm and control arm may be varied by means of adjusting screw 80.

I claim:

1. In a control arrangement, a condition-responsive device including a movable index, a depressor movable in a path intersecting the path of movement of said index and having two different ranges of movement depending upon its contact with or absence of contact with said index, a reversible lever system including two interacting levers, the depression of either of said levers effecting the elevation of the other lever, actuating means selectively positioned in response to the particular range of movement of said depressor to depress a predetermined one of said levers, and mechanism selectively actuated to different positions by the respective movement of said levers.

2. In a control arrangement, a condition-responsive device including a movable index, a depressor movable in a path intersecting the path of movement of said index and having two differ-

ent ranges of movement depending upon its contact with or absence of contact with said index, a reversible lever system including two interacting levers, the depression of either of said levers effecting the elevation of the other lever, a member mounted on said depressor and selectively movable thereon to either of two positions in response to the range of movement of the depressor, and means in said levers engageable by said member in its respective positions to effect the respective depression of said levers.

3. In a control arrangement, a condition-responsive device including a movable index, a depressor movable in a path intersecting the path of movement of said index and having two different ranges of movement depending upon its contact with or absence of contact with said index, a reversible lever system including two interacting levers mounted on a common axis, the depression of either of said levers effecting the elevation of the other lever, a member mounted on said depressor and selectively movable thereon to either of two positions in response to the range of movement of the depressor, and projections on said levers.

4. In a control arrangement, a condition-responsive device including a movable index, a depressor movable in a path intersecting the path of movement of said index and having two different ranges of movement depending upon its contact with or absence of contact with said index, a bell crank lever for periodically lowering said depressor, a member pivotally mounted on said depressor, a pin on said member in position to be engaged on one side by said lever, and on the other side by a fixed stop, the engagement of said pin by said lever serving to position the member in one position and the engagement of said pin by said stop serving to position said member in a second position, and means selectively adjusted in response to the respective positions in which said member is actuated.

5. In a control arrangement, a condition-responsive device including a movable index, a depressor movable in a path intersecting the path of movement of said index and having two different ranges of movement depending upon its contact with or absence of contact with said index, a reversible lever system including a first lever and a second lever mounted to rock about a common axis, pins projecting from the adjacent ends of said levers, a third lever having one end rocking about a fixed pivot and being pivotally connected at its other end to a point adjacent one end of said first-mentioned lever, said third lever being connected at an intermediate point thereon to an end portion of the second lever, said points of connection being located at opposite sides of said axis, and a member movable to alternate positions by the actuation of said levers.

6. In a control arrangement, a condition-responsive device including a movable index, a depressor movable in a path intersecting the path of movement of said index and having two different ranges of movement depending upon its contact with or absence of contact with said index, a reversible lever system including a first lever and a second lever mounted to rock about a common fixed axis, a third lever having one end rocking about a fixed axis, two pivotal connections to movable portions of said third lever, said connections being respectively located at opposite sides of said fixed axis, one of said pivotal connections being to one end of said first lever and the other pivotal connection being to the opposite end of

said second lever, and a member movable to alternate positions by the actuation of said levers.

7. In a device of the class described, a condition-responsive mechanism, a member to be actuated, and protective means interconnecting said mechanism and said member, said means comprising two arms rotatably mounted, one of said arms being connected to said mechanism and the other arm being connected to said member, and resilient means normally maintaining said arms in a single given angular relation.

8. In a device of the class described, a condition-responsive mechanism, a member to be actuated, and protective means interconnecting said mechanism and said member, said means comprising two arms mounted to rotate about a common axis, one of said arms being connected to said mechanism and the other arm being con-

nected to said member, and resilient means normally maintaining said arms in a single predetermined angular relation.

9. In a device of the class described, a condition-responsive mechanism, a member to be actuated, and protective means interconnecting said mechanism and said member, said means comprising a first arm and a second arm mounted to rotate in superimposed relation, said first arm being connected to said mechanism and said second arm being connected to said member, a third arm rotatably mounted adjacent said first and said second arms, and resilient means normally causing said first arm to engage one side of said third arm and other resilient means normally causing said second arm to engage the other side of said third arm.

JULES A. WIDMER.
